UNITED STATES PATENT OFFICE.

JOHN B. TYTUS, OF MIDDLETOWN, OHIO, ASSIGNOR TO THE AMERICAN ROLLING MILL COMPANY, OF MIDDLETOWN, OHIO, A CORPORATION OF OHIO.

ANNEALING PROCESS.

Application filed May 1, 1923. Serial No. 635,985.

My invention relates to methods of annealing sheet metal, and also to methods of preparing sheet metal for continuous processes of heat and acid treatment, including 5 washing, brushing, drying, cleaning and the like.

In the handling of sheet metal in a continuous manner in heat and acid treatment, the cumbersome nature of the article handled 10 has presented great difficulties to the art. There have been methods of annealing wire, and strip metal wherein the long pieces delivered to the pickling tanks in rolls, are unwound and rewound so as to draw them 15 through the tanks of acid, and occasionally it has been the practice to stitch or tie together in some convenient manner the ends of the strips or strands, so as to avoid the necessity of leading each new roll of material through 20 the tanks before starting the pickling.

It is one of my objects to stitch together sheets of metal as distinguished from strips, strands or bands, and in this way to form a continuous piece that can be carried by rollers and pinch rolls, through various steps of 25 treatment:

It is a comparatively simple problem to handle wire or strip metal for annealing, heat treating and pickling, since the piece is long 30 and can be treated as if practically endless. Sheets in the steel rolling mill have such characteristic action during the process of attenuation, however, that they have fallen into an entirely different category.

Briefly stated, the processes of rolling wide metal pieces into thin gauge, must of 35 necessity use small length pieces and limit the amount of attenuation in the rolls to definite lengths. The peculiarities of the action of 40 mill rolls, and the nature of temperatures of the pieces being reduced and several other factors, result in a different attenuation of a piece down the middle and along the edges. This difference accumulates as a piece passes 45 through the rolls and if the piece is long enough, will result in a buckling of the metal, and often in a broken mill. Progress in the rolling of strips has been made along the line of producing wider pieces of continuous 50 character than was thought possible fifteen years ago, but there is still a very distinct limit in width in continuous strip production.

Sheet is the term applied to the thinner

gauges of metal produced in short wide pieces by processes which begin at the several 55 stages of reduction with even shorter pieces. Each sheet is necessarily unfinished at the front edge and the back edge from its passage as a single entity through the rolls. In strip production, however, length is limited 60 mainly only by convenience in handling of the product on the final reels, since the process of reducing the original bar or ingot into strip is in a single piece.

In speaking of sheets in this application 65 then, I use the term to distinguish metal pieces which are produced with process limitation as to length, primarily because of the width and thinness of the pieces, from 70 metal pieces known as strips, which from necessities of process have limitations in width and gauge but no limitation as to length.

The art involving the production of sheet metal is replete with expensive mechanical 75 devices for transporting sheets through heat and acid treatments, all of which are devoted to the manipulation of thin, short length, wide pieces. It has never occurred to those skilled in the art, that since all sheets due to 80 necessities of process have an unfinished edge at both ends, that they could be welded or stitched together into a continuous piece, using the unfinished ends for this purpose, 85 without waste.

It has been advocated in strip and wire pickling and heat treating, that after one strip or strand has all but passed through the process, that another strip or strand be hitched to it, to avoid necessity of feeding 90 the beginning of the next strip or strand into the machine. The use of waste ends in wire and strip work, for this purpose, has never been mentioned, however, and in fact the waste would be so little in proportion that its 95 conservation would be absurd, as compared to sheets in which the waste ends, on an average careful rolling will be around 6% at least.

It is a demonstrated fact that certain heat treatments, such as are employed for softening and taking out strains in steel sheets can best be done by an individual heating, as distinguished from heating in a pile, as is done in box annealing. However, to individually treat in this way a number of sheets in a 100 continuous furnace, requires the use of a very 105

closely arranged body of driven rolls, so that the sheet which often shows some tendency to bend down or curl, will not work down between the rolls, and thus block the action of the furnace. The roll upkeep is quite costly as the lives of the rollers within a furnace are short, due to the temperature that must be carried.

There are other individual sheet annealing devices, using various ways of handling the pieces but these are all expensive and inconvenient.

One of the objects of my process is to continuously anneal a series of sheets of metal, and to do this with a continuous piece formed of a number of sheets secured end to end. By this method I can draw sheets through a furnace without any mechanism within the furnace, and in long furnaces where rollers are desirable, I can dispense with all but a very few rollers.

Another object of my invention is to produce a long strip of sheets without loss of any metal due to the necessity of cutting away the stitched or welded joints between the individual pieces. In this connection also it is my object to facilitate the production of a continuous ribbon of sheets, so that the side edges will be aligned and the long body will not twist and buckle due to an un-uniform stitching.

I believe that I am the first to provide a continuous strip made of sheet metal, for treatment in the rolling mill plant, and I mean by sheets, pieces of metal which because of width and gauge required in the final product are impractical to produce by the strip process. Expressing this matter in another way, my object is to proceed by the sheet rolling process so far as requirements for successful reduction of the thickness of a wide piece are concerned and then to convert the material into a piece which can be handled in a continuous band, in that portion of the processing where reduction between rolls is not required.

I accomplish the objects set forth above and the advantages to be detailed, by that certain process of handling, and treatment to be hereinafter more specifically pointed out and claimed.

In the drawings:

Figure 1 is a plan view of a portion of a continuous piece formed of sheets of metal.

Figure 2 is a like view of a single sheet trimmed and ready for securing into a strip with other sheets.

Figure 3 is a diagrammatic view of a mechanism which may be used in my process.

Referring to the first two views, I have shown pieces of sheet metal 1. As produced in the rolling mill these sheets will have at both ends distorted portions 2, 2, which cannot be left in the final products.

These ends are trimmed as a first step in

my process, but this trimming is done so as to leave a straight edge 3, 3, at each end of the piece, which edge is still well outside of what will have to be the final trim on the sheet. Thus it will be noted that in the view shown, the corners of the sheet as at 4, are still cut-away or rounded off, after this trimming has taken place, also there is an indentation at 4^a on one end (Figure 2). I have indicated by the dotted line 5, the final trim line, in preparing the sheet for the customer. The roller allows for sufficient extra metal in his sheets, among other reasons, so that the ends will not have to be cut back far enough to destroy the ultimate length for which he is finishing, and to avoid entire sheets being wasted, has to leave more metal in the sheet than might possibly be necessary to get out a full length piece after trimming. This leaves sufficient metal for it to be possible to trim back every sheet to a straight edge as shown or other conformation, leaving a still further amount which requires to be removed at a final trimming.

The sheets trimmed, as now described to a straight edge, are then formed by stitching or welding into a long continuous piece, in which the sheets are secured end to end. The operator has a clean edge to go by in lining up the pieces for securing the front end of one to the rear end of the other, and also knows just how far he can lap one piece over the other in forming his connecting joint, as this is provided for in the first trimming. That is to say, that the first trimming will be such as to leave, say an inch of material on each end of each sheet, which will have to be removed to leave the length called for by order being rolled and this inch is to be used in overlap.

After having the sheets so formed the long, or continuous piece can be handled in annealing, washing, drying, pickling and the like, all of said treatments being continuous, thus saving great time, and a great expense in equipment. When the long piece has been treated, the final work thereon will be to chop it across by a shears, in which for example a double edged blade can be used, which will be so guided as to cut out of the long strip those portions of each sheet which are used in making the joint. With a definite trimming in the first place, and a proper location of the lap, if any, between the sheet ends, the correct amount for cutting out by the final shears can be arranged.

I do not wish to limit myself to a lap joint or to a straight edge to which the individual pieces are first trimmed, as the edge might be of various conformations depending upon the joint it was desired to make, the prime consideration being that the first trim should be arranged to give meeting or lapping edges which bear definite and predetermined relation to the final trim so that the operator

can leave enough metal over the final length to permit a subsequent cutting out of the jointed portions.

The annealing feature of my invention and the stitching process, are best described from the view of Figure 3. In this view a table 10 is shown upon which are a pile of sheets 1. There is a table 11, and a shears 12, the operator picking up a sheet at a time and trimming them to the edge and the dimensions desired, as above described. From the shears, the pieces pass under a welder or stitcher 13, where the ends are secured together, the long piece being then led to the furnace 14. In this furnace the rollers 15 may be spaced apart fairly widely, and some of them, if desired, not driven, while others are revolved. Pinch rolls 16 may be located at each end of the furnace to accomplish a positive speed of movement of the long piece made up by joining the sheets. By the word "treating" in the claims that follow, I refer to the annealing, pickling, washing and drying processes, which are given to sheet metal in order to give it the desired characteristics, which the rolling of the metal do not produce.

I have not shown any subsequent diagrams of washing, drying, and pickling devices, nor have I shown further the shears for cutting out the jointed portion of the sheets.

Having thus described my invention, what I claim as new and desire to secure by Letters Patent, is:—

1. In a metal heat treating process those steps which consist in rolling a body of metal which, when rolled to the gauge required by a given order, will have a length which is in excess of the ordered length by an amount sufficient to allow for terminal irregularities necessarily incident to the rolling process, then uniting the individual sheets end for end utilizing the said excess, so as to leave between each union a body of metal of the length required by the said given order, passing the continuous band so provided through a heat-

ing chamber, and finally cutting away the zones of union, leaving individual pieces of the said required length.

2. In a metal heat treating process those steps which consist in rolling a body of metal which, when rolled to the gauge required by a given order, will have a length which is in excess of the ordered length by an amount sufficient to allow for terminal irregularities necessarily incident to the rolling process, trimming the irregular excess ends of the individual sheets to lines which will serve as guides in uniting the sheets in a straight line, then uniting the individual sheets end for end utilizing the said excess left after said trimming, so as to leave between each union a body of metal of the length required by the said given order, passing the continuous band so provided through a heating chamber, and finally cutting away the zones of union, leaving individual pieces of the said required length.

3. In a metal heat treating process those steps which consist in rolling a body of metal which, when rolled to the gauge required by a given order, will have a length which is in excess of the ordered length by an amount sufficient to allow for terminal irregularities necessarily incident to the rolling process, trimming the irregular excess ends of the individual sheets to lines which will serve as guides in uniting the sheets in a straight line, said lines being arranged so as to be an equal distance from the ends of a full width intermediate zone of the length of the given order, then uniting the individual sheets end for end utilizing the said excess left after said trimming, so as to leave between each union a body of metal of the length required by the said given order, passing the continuous band so provided through a heating chamber, and finally cutting away the zones of union, leaving individual pieces of the said required length.
